A. L. WEIS AND W. H. RAY,
METAL BOUND FIBER CONTAINER,
APPLICATION FILED NOV. 5, 1919.

1,394,592.

Patented Oct. 25, 1921.

UNITED STATES PATENT OFFICE.

ANDREW L. WEIS AND WILLIAM H. RAY, OF MONROE, MICHIGAN, ASSIGNORS TO THE WEIS FIBRE CONTAINER CORPORATION, OF MONROE, MICHIGAN, A CORPORATION OF SOUTH DAKOTA.

METAL-BOUND FIBER CONTAINER.

1,394,592.

Specification of Letters Patent.

Patented Oct. 25, 1921.

Application filed November 5, 1919. Serial No. 335,845.

To all whom it may concern:

Be it known that we, ANDREW L. WEIS and WILLIAM H. RAY, citizens of the United States of America, and residents of Monroe, Michigan, have invented a certain new and useful Improvement in Metal-Bound Fiber Containers, of which the following is a specification.

This invention relates to containers in general, but more particularly to those which are adapted to hold liquids, and especially to pails made of sheet material, such as fiber board or other similar material.

Generally stated, the object of the invention is to provide an improved construction and arrangement whereby a pail or similar container of this character may be economically manufactured from fiber board or similar material and reinforced with metal binding in a manner to insure a strong and serviceable article, as well as one that will present a good appearance and be otherwise satisfactory in use.

It is also an object to provide certain details and features of construction and combinations tending to insure greater efficiency and desirability for a metal bound fiber pail of this particular character.

To these and other useful ends the invention consists in matters hereinafter set forth and claimed and shown in the accompanying drawings, in which—

Figure 1 is a side elevation of a pail embodying the principles of the invention, showing the right hand side portion thereof in vertical section.

Fig. 2 is an enlarged detail or fragmentary section.

Fig. 3 is a side elevation of the structure shown in Fig. 2.

Fig. 4 is an enlarged detail or fragmentary section.

As thus illustrated, the invention comprises a downwardly tapered body 1 to which the bail-shaped handle 2 is secured by means of brackets 3 riveted to the fiber or other sheet material from which the body is made. Said brackets 3 are preferably made of sheet metal and provided with struck out portions 4 which form eyes for the hooks 5 of said handle, so that the latter is free to swing in either direction. The rivets 6 extend through the sheet metal and fiber directly above and below the portion 4, and securely hold the two brackets in place

at opposite sides of the pail. The bottom of the pail is formed by a lower wall 7 which is of a diameter to extend under the lower edges of the body 1, and an inner or upper wall 8 which is of a diameter to fit within the body 1, so that the lower edges of the latter are held against being crushed or pressed inward. The bottom of the pail is reinforced by a metal binding in the form of a hoop 9 which has its lower edge 10 curled inward and upward to engage the lower surface of the wall 7, so that the latter is held tightly against the lower edges of the body 1, thus forming a liquid tight joint. This binding is fastened in place by portions 11 of the metal which are pressed or punched inward, and in addition the upper edge 12 of the metal hoop thus formed is pressed into the fiber of the body. With this construction the metal binding is held firmly in place at the bottom of the pail, and the curled lower edge of the binding forms a rounded annular edge upon which the pail rests when placed upon a floor or other surface. Only the metal binding extends below the bottom, and the wall 8 of the bottom keeps the loose end of the body in expanded condition, while this expansive force is counteracted by the restraining influence or effect of the sheet metal binding. The wall 8 resists the pressure necessary to force the portions 11 into the pail.

The pail thus constructed can be used for various purposes. For some purposes, however, a cover is necessary. As shown, a cover is provided in the form of a disk 13 of fiber or other suitable material. Said disk is large enough to rest upon the upper edges of the body 1 and slightly overhang the outer surface of the latter. To make the cover tight, metal binding in the form of a ring 14 is provided, it being observed that this ring is formed of sheet metal and bent around the edges of the disk or cover 13, so that it lies flatwise upon the upper surface of the latter; and, in addition, this metal binding is formed with a depending portion 15 which encircles the top portion of the body 1, so that the cover as a whole has a depending rim which fits the top of the pail. With this construction a simple and efficient cover is provided which tightly seals the top of the pail. Any suitable means can be employed for holding the cover in place, if such is necessary or desirable.

From the foregoing it will be seen that a novel and simple construction is afforded whereby a pail or other container may be made from fiber or similar sheet material, 5 effectively reinforced with sheet metal, so that containers of this character may be economically manufactured in large quantities. At the same time, however, the materials and the construction are such that 10 the pail is not only strong and serviceable in use, but light and satisfactory in other ways, the construction insuring also a good appearance. It will be understood, of course, that the body 1 is round in horizontal cross 15 section, like an ordinary pail. By tapering the body downwardly it is obvious that the pails can be nested together for shipment. The exact character of the fiber or other material employed for the body of the pail, 20 and for the cover and bottom thereof, is dependent upon the particular purpose or use for which the pail is to be employed. The fiber can be hard or more or less soft, and it may be saturated or coated with paraffin or 25 varnish or other preservatives, to make the pail water or liquid proof, in any suitable or well known manner.

What we claim as our invention is:—

1. A container comprising a fiber body 30 forming the sides of the container, a bottom which keeps the lower end of said body in expanded condition, and sheet metal binding in the form of a hoop which counteracts the said expansion of the body by the bottom 35 and which reinforces the lower edges of said body and which has a lower channel portion forming a hollow annular base for the container and for holding said bottom in place, with the outer edge of the bottom 40 engaging the outer side wall of the hoop and with the inner edge of said base engaging the inner surface of said bottom.

2. A structure as specified in claim 1, said body being round in horizontal cross section, 45 and tapered downwardly to form the body.

of a pail, in combination with a bail-shaped handle attached to the upper portion of said body.

3. A structure as specified in claim 1, said bottom comprising a lower wall which extends under the lower edges of said body, so that only the metal binding extends below the bottom, and an upper wall which fits the interior of said body, said upper wall and said metal binding coöperating to hold 50 the lower edges of the body against either inward or outward displacement, and said metal binding having portions thereof pressed into the body above said upper wall to hold the hoop in place. 60

4. In a container, the combination of a fiber body forming the sides of the container, a bottom, means for holding the bottom in place, a cover in the form of a disk resting upon the upper edges of said body, and extending beyond and overhanging the outer sides thereof, and a sheet metal binding in the form of a ring adapted for reinforcing the edges of said cover, a portion of said binding resting flatwise upon the upper surface of the cover and over the upper edges of the container, another portion of the binding extending around and under the edges of the cover, and another portion of the binding extending downward to fit around the upper 70 end of said body, so that said binding forms a permanent part of the cover and removably engages the top of the container.

5. In a container, a fiber body forming the sides of the container, sheet metal brackets having struck out strip portions which form eyes, rivets above and below said eyes to secure the brackets in place with their backs to the body, so that each eye is open at opposite sides of its struck out strip portion, and a bail-shaped handle having hooks for engaging said eyes together with a bottom for said container.

ANDREW L. WEIS.

WILLIAM H. RAY.
